UNITED STATES PATENT OFFICE.

CHRISTIE M. SHEPHERD, OF INDIANAPOLIS, INDIANA.

CAR-DOOR.

SPECIFICATION forming part of Letters Patent No. 766,737, dated August 2, 1904.

Application filed October 30, 1903. Serial No. 179,251. (No model.)

To all whom it may concern:

Be it known that I, CHRISTIE M. SHEPHERD, of Indianapolis, county of Marion, and State of Indiana, have invented a certain new and 5 useful Car-Door; and I do hereby declare that the following is a full, clear, and exact description thereof, reference being had to the accompanying drawings, in which like numerals refer to like parts.

10 The object of this invention is to provide a car-door construction wherein the door fits flush, that will effectually keep out the moisture, rain, and sparks.

15 The full nature of this invention will be understood from the accompanying drawings and the following description and claims.

In the drawings, Figure 1 is a side elevation of a portion of a railway-car, showing the door closed, the means for removing and 20 replacing the door being omitted. Fig. 2 is a vertical section on the line 2 2 of Fig. 1. Fig. 3 is a transverse section on the line 3 3 of Fig. 1. Fig. 4 is a portion of what is shown at the upper end of Fig. 2, but on a 25 larger scale. Fig. 5 is a portion of what is shown at the left-hand side of Fig. 3, but on a larger scale.

In detail, 10 is a car and 11 is a car-door. Suitable means would have to be provided for 30 removing and replacing this door; but since such means constitutes no part of this invention the same has been omitted for the sake of clearness.

The car is provided with a door-casing consisting of a top 12, the sides 13, and the bottom 14. These are all beveled on their inner surfaces, so that the door will wedge into place.

The door 11 is placed on a frame consisting 40 of a top piece 15, side pieces 16, and a bottom piece 17, that are externally beveled to correspond with the beveled surfaces of the door-casing.

On each side of the door there is placed a 45 metal strip 18, extending laterally beyond the edge of the door and overlapping the boards 19, forming a part of the car and door-casing. The lateral edges of the door are externally beveled somewhat at the point where the over- 50 lapping metal strips 18 are secured, and the

strips 19 of the door-casing are provided with a vertical recess 20, that forms a seat for the overlapping metal strip 18 to fit in. This construction, combined with the beveled construction of the door-casing and door, prevents water or the like entering the sides of the door.

The top of the door is likewise externally beveled and provided with a horizontal metal strip 21, that fits in a recess 22, formed in the 60 lower edge of the timber or piece 23, which forms a part of the upper portion of the door-casing, being secured horizontally to the timber 12. The lower edge of the piece 23 has an upwardly-extending longitudinal groove 65 24 in front of the position occupied by the metal strip 21, so as to leave a shoulder at 25, under which the upper edge of said metal strip is located, and an overhanging ledge 26 in front of the groove. The purpose of this construction last described and shown best in Fig. 4 is to prevent the rain as it runs down the side of the car and the side of the upper cross-piece 23 from entering the car above the door and between the door and upper part of the 70 door-casing. In this construction the water will drip from the ledge 26, and the groove 24 will effectually keep the water from coming into contact with the shoulder 25 or other inner part of the door-casing and will also 75 keep it out of contact with the upper edge of the metal strip 21, and since that metal strip is inclined downwardly and outwardly it will shed all the rain or water that comes into contact with it below its upper edge.

80 What I claim as my invention, and desire to secure by Letters Patent, is—

1. The combination of a car or the like and a flush door, the casing above and adjacent the top of the door having a centrally and upwardly extending groove so as to form an outward overhanging ledge and the upper edge of the door being beveled and having secured to it a metal strip that is inclined inward and upwardly and fits in said door-casing behind 90 said groove.

2. The combination with a car having a door-opening with a surrounding casing provided with beveled surfaces on all four sides, the upper door-casing having a recess in it with 95 100

an upwardly-extending longitudinal groove forming an outward overhanging ledge, and the sides of the casing having vertically-extending recesses, and a door with a beveled frame and the outer lateral top edges of said door being also beveled, and metal strips secured to said outer beveled portions of the door so as to extend inward somewhat and beyond the door, the lateral metal strips fitting in the recesses in the side casings, and the up-

per metal strip fitting in the recess in the upper casing behind the upwardly-extending longitudinal groove therein.

In witness whereof I have hereunto affixed my signature in the presence of the witnesses ¹⁵ herein named.

CHRISTIE M. SHEPHERD.
